(57) **CLAIM**

The ornamental design for a combined wrist and arm training tool, as shown and described.

DESCRIPTION

FIG. 1 is a front view of the combined wrist and arm training tool showing my design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof;

FIG. 8 is a sectional view at cross-section 8-8 of FIG. 1;

FIG. 9 is a sectional view at cross-section 9-9 of FIG. 1;

FIG. 10 is a sectional view at cross-section 10-10 of FIG. 1;

FIG. 11 is a reference diagram showing the usage of a combined wrist and arm training tool; and,

FIG. 12 is a reference diagram showing a perspective view of the combined wrist and arm training tool laying flat with the central palm holding band removed.

The human hand shown in broken lines in FIG. 11 is for the purpose of illustrating environmental structure, which forms no part of the claimed design.

1 Claim, 6 Drawing Sheets
